UNITED STATES PATENT OFFICE.

FREDERICK A. OST, OF MINNEAPOLIS, MINNESOTA.

CARBURETER.

1,347,052.

Specification of Letters Patent. Patented July 20, 1920.

Application filed July 6, 1914, Serial No. 849,125. Renewed December 8, 1919. Serial No. 343,425.

To all whom it may concern:

Be it known that I, FREDERICK A. OST, a citizen of the United States, residing at Minneapolis, in the county of Hennepin and 5 State of Minnesota, have invented a new and useful Improvement in Carbureters, of which the following is a specification.

My invention relates to carbureters for internal combustion engines, the principal 10 object being the use of kerosene or denatured alcohol in internal combustion engines, it being readily understood that gasoline can be used with my invention.

A further object is to provide an air 15 valve connected with an oil supply valve, and arranged to open said oil supply valve, a predetermined distance without admitting a proportionate volume of air.

A further object is to provide efficient 20 vaporizing means whereby heavy oils are adapted to be carbureted and wherein heating of the vaporizing surfaces is accomplished, so that the oil can be vaporized when the engine is being started.

25 Further objects of and advantages attained by my invention will be apparent from the following description.

In the accompanying drawings forming 30 part of this specification, Figure 1 is a vertical sectional view through a carbureter embodying my invention; Fig. 2 is a horizontal section taken on the line X—X, Fig. 1; Fig. 3 is a vertical section of a detail; Fig. 4 is a horizontal section on the line 35 Y—Y, Fig. 3, and Fig. 5 is a vertical section on the line Z—Z, Fig. 4.

In the drawings, 2 indicates an inner casing, having a cylindrical body 3 formed with a conical upper end 4, a pair of lower 40 laterally extending elbows 5 and 6 and an inner vertical gasifying tube 7, said tube being provided with a vertical central passage 8 in which a longitudinally channeled valve stem 9 is arranged. The lower portion 45 of said casing is closed by a bottom plate 10, which is detachably secured to the casing by screws 11, a centrally disposed passage 12 being provided in said plate through which said tube 7 depends. The 50 upper portion of the casing 3 is surrounded by an outer casing 13, which is spaced a short distance from the outer wall of the inner casing to form a vaporizing chamber 14, in which air is drawn upwardly 55 through openings 15, (see Fig. 2), between the walls of the inner and outer casings,

The lower end of said outer casing is formed with a pair of flanges 16, which are seated upon and secured to the lower portion of the inner casing, such as by screws 17. 60 The space within the inner casing and surrounding the tube 7 forms a reverberatory chamber in which unconsumed and burning gases exhausting from a combustion engine rebound, coupling elements 5 and 6 connected with the exhaust pipe of said combustion engine, (not illustrated), being provided for conducting said gases through said chamber. The upper end of the outer casing is tapered inwardly to correspond with the inward inclination of the conical upper end of the inner casing, and is formed with a neck 18, which flares outwardly in an upward direction, and is formed with a horizontal valve seat 19, to 70 receive the air valve 20. This valve is adapted to control the opening of the upper end of the vaporizing chamber and has a hub 21 that is slidably mounted on the upper portion of the stem 9. The periphery 75 of the air valve is flanged upwardly and adapted to slide vertically in a cylindrical wall 22 extending upwardly above the valve seat 19, in the neck 18. The valve 20 is also provided with a pair of bosses 23, (see 80 Fig. 4), to which are pivotally attached the lower ends of a yoke 24, said yoke carrying upon its neck freely rotatable anti-friction rollers 25, part of which actuate a lifter 61 to raise the valve 9, as will be 85 hereinafter described. The cylindrical wall 22 is integral with an upper inclosing wall 26, which forms a chamber through which the full vapor arising from the vaporizing chamber 14, passes upwardly and through an 90 outlet passage 27, which may be connected to the fuel manifold or combustion chamber of the engine not illustrated, said passage 27 being provided with the usual butterfly valve of suitable construction, such as 95 28, which is carried by a shaft 29 journaled in the walls of the structure, and provided with an operating arm 30 or other suitable means by which the valve can be regulated to admit the desired quantity of fuel mixture into said combustion chamber or manifold. 100

The floor 10 is formed with upwardly extending partition walls 31, which terminate a short distance from the upper end of the 110 vaporizing chamber within the inner casing and act as baffle plates against which the

hot gases egressing from the exhaust of the engine impinge and are deflected upwardly through the entire reverberatory chamber, so as to utilize a maximum amount of heat 5 for raising the temperature of the inner wall 3, and thus substantially complete the vaporizing of the partly vaporized oil quickly which spreads downwardly over the surface of the inner wall within the vapor 10 izing chamber 14.

Secured to the outer casing such as by the bolt 36, or other suitable means, is an oil supply receptacle 35, said receptacle being provided in its lower end with an opening 37, having a valve seat 38, which is closed by a valve 39 moving upwardly. The valve 39 has a stem 40 extending upwardly in the receptacle and guided by its upper end through a cover 41, and carrying 15 a float 42, which regulates the height of the oil or hydrocarbon fluid in the receptacle, which is maintained through the opening and closing of valve 39. A suitable supply pipe such as 43 is joined such as by the 20 union 44 to the portion of the receptacle containing the valve seat 38, by which the fuel admitted to the carburetor is conducted. The receptacle has an outlet duct 45, which is joined by a union 46, and a 25 bushing 47, seated in the lower end of the gasifying tube 7. This bushing has its passage 48 connected with said duct, said passage being opened and closed by the needle valve 49, which is formed on the lower end 30 of stem 9. The lower end of the valve stem which is formed with the needle valve 49 projects downwardly through a partition 50 across the passage 8 into a chamber 51 in the lower end of said tube, said chamber 35 being connected with a pre-heating tubular coil 52, which conveys the fuel when the valve 49 is opened to the passage 8 above said partition 50, said coil being looped upwardly over one of the baffle walls 31, so as 40 45 to raise the temperature of the fuel liquid in said coil quickly. The upper end of the conical portion of the inner casing is formed with an upwardly and outwardly slanting surface 55, and the lower end of the hub 21 50 is formed with a corresponding slanting wall 56, said walls forming an upwardly and outwardly slanting passage, which is adapted to spray the mixture of fuel liquid and gas received from the passage 8 into 55 the space surrounded by the neck 18, from whence the liquid fuel descends upon the heated surface 4 of the inner casing and the gas ascends. It will be noted that the diameter of the lower end of the valve stem 9 is 60 less than the diameter of the passage 8 and chamber 51, so that there is free connection with the ducts leading into or from said passages. It will also be noted that the upper portion of the valve stem passing 65 through the opening 8 is formed with longi-

tudinal channels 57, which nearly coincide with the lower edge of the wall 55, so that there is free communication between passage 8 and chamber 14. The conical surface 4 on the inner casing within the chamber 14 is formed with concentric circular ridges 58, forming grooves stepped apart upwardly which serve to catch the fuel liquid received from pre-heating coil 52 and the passage 8 and retain the same until it 70 has been thoroughly gasified and mixed with air. The action of the valve 20 is automatic through the drawing up of air and fuel mixture produced by the suction stroke of the engine, the distance the valve 20 80 opens being controlled by regulating an auxiliary air ingress valve 80. The upper end of valve stem 9 has a head 60, said head and stem being raised by a lifter 61 which has a cam surface 63 against which two of 85 the antifriction rollers 25 press to tilt the lifter, said lifter being journaled between its ends upon a pivot bearing 62 on a support 67 carried by the inclosing wall 26. One end of the lifter is arranged below the 90 head 60 and the other end having the cam surface 63 is placed in the path of movement of said rollers 25. A bell crank lever 64' is pivoted at its angle upon the shaft 65 passing through a carriage 66, said carriage being gibbed upon said arm 67, which is secured on the frame of the inclosing wall 26 by means of screws 68. One arm 64 of the bell crank lever 64' acts as an adjustable guide surface inclining upwardly 95 and inwardly, for the purpose of adjusting the amount of opening of the needle valve 49 on valve stem 9. A spring 69 between an extending arm 63² on the carriage 66 and one of the arms 63³ of the bell crank lever 100 serves to always hold the guide surface of the bell crank lever back against a regulating stop pin 70, said stop pin being threaded in the inclosing wall 26 and passing freely through the carriage 66, so that 105 the amount of inclination of the guide surface on the bell crank lever may always be regulated in distance away from the cam surface 63. The position of the carriage 66 is slidably held on the support 67 by a screw 110 71, which has its outer end threaded into the carriage and its head seated in the inclosing wall 26. A spring 72 on the shank of the screw 71 is interposed between the inclosing wall 26 and the carriage 66, 115 whereby the carriage is urged forward the full extent which the screw 71 permits. It will be noted by regulating the screw 71, the time at which the valve 9 starts to open 120 is regulated, and that the amount of inclination of the guiding surface of the bell crank lever 64' determines the length of interval lapsing between the time when the valve 49 starts to open and when it reaches wide open position. 125

For the purpose of priming the device, the valve 9 may be opened by hand when starting, by depressing a pin 75, which is slidably mounted in the inclosing wall 26 5 and passes freely through the carriage with its inner end directed toward the free end of a lug 63' on the cam surface 63 of the lever 61. This pin is held normally out of operation by the spring 76 interposed between 10 its head 77 and the outer surface of the inclosing wall 26, whereby inward depression of said pin tilts the lever 61 and opens the valve 9.

The vapor chamber formed by the inclosing wall 26 is provided with an auxiliary air inlet valve 80, seated in its wall, which is held normally closed by the springs, 82 and 83, seated above a cap 84 on the outer end of its stem, the inner ends of said 15 springs bearing respectively against the hub 85 on the support 86, through which the stem slides freely and against an adjusting nut 87, which is threaded on said hub; so that when turned, the compression of the 20 spring 82 is regulated. The valve 80 remains closed during the working stroke of the piston of the engine, but opens automatically during the suction stroke to admit a predetermined amount of air, which mixes 25 with the fuel entering the engine according to the force urged against the valve by the springs 82 and 83.

Situated above the adjusting mechanism in the chamber formed by the casing 26 is 30 a relief valve 95 seated in the casing wall and held closed by a restraining spring 96 below a valve cage 97, which is threaded into engagement with said wall. In case of 35 back firing due to premature explosion in the chamber formed by said casing 26, the relief valve is opened automatically and releases the pressure of burning gases.

The gasifying tube 7 may be preheated to assist in vaporizing the fuel by means independent of the exhaust gases from the engine passing through the reverberatory chamber. This means may be in the form of an electric coil such as 90 mounted upon the gasifying tube 7 and embedded in insulation such as asbestos, enamel or other suitable material 91. The ends of this coil forming electric conductors may be connected with a suitable source of electric power not illustrated, for the purpose of 45 energizing the coil and heating the gasifying tube, so that when starting the engine with kerosene or other heavy or light oils or alcohol, the fuel liquid is raised to a gasifying temperature, so as to readily mix with 50 the air passing into the carburetor. As illustrated one end of the circuit is shown grounded upon the metal frame work of the structure, while the other end is led outwardly through an insulating bushing 55 92, in the bottom plate 10. It will be noted

that the bottom plate 10, pre-heating tube 52, and the electric pre-heating coil 90 may be removed from the apparatus for cleaning, repairing or replacing parts when desired.

It will be further noted that kerosene carbonizes and is refined when heated leaving a deposit which in the structure set forth collects around the stem 9 in its grooves. For ease in cleaning the stem, the structure 70 75 is provided with the design of lever 61 shown whereby the roller 25 may be swung back clear of the stem and the stem lifted out through the valve passage 95 above the stem. After cleaning the stem it may easily be replaced.

To release abnormal pressure in the carburetor due to back firing, a valve 96 is seated in the passage 95 and held by the spring normally closed, said spring being 80 seated below the valve cage 97. To remove the valve 96, the cage 97 is removed.

In accordance with the patent statutes, I have described the principles of operation of my invention, together with the apparatus which I now consider to represent the best embodiment thereof, but I desire to have it understood that the construction shown is only illustrative, and that the invention can be carried out by other means 95 and applied to uses other than those above set forth within the scope of the following claims.

What is claimed is:—

1. A carburetor, comprising, in combination, inclosing walls forming inner reverberatory and outer gasifying chambers, said inner chamber being formed with an inlet and an outlet for the ingress and egress of exhaust gases and said outer chamber 100 having an inlet and an outlet for the admission of air and the egress of fuel mixture, said inner chamber being formed with a long fuel gasifying tube depending downwardly therein having its lower end adapted 105 to be connected with a source of fuel supply and its upper end connected with said outer chamber, a valve seated in said tube and adapted to close the passage in its lower end and having a long stem extending upwardly 110 through said passage and provided with a channel in its side whereby residue in the passage of said tube from the passage of fuel mixture therethrough is collected, said valve being removably mounted in said tube, 115 whereby said channel can be cleaned and means for opening and closing said valve.

2. A carburetor, comprising, in combination, inclosing walls forming inner reverberatory and outer gasifying chambers, said inner chamber being formed with an inlet and an outlet for the circulation of exhaust gases through said inner chamber and said outer chamber having an inlet and an outlet 125 for the admission of air and the egress of 130

- fuel mixture, said inner chamber being formed with a fuel gasifying tube depending downwardly therein having its lower end adapted to be connected with a source 5 of fuel supply and its upper end connected with said outer chamber, a preheating coil interposed between the lower and upper portions of said passage in said tube, said coil being arranged in said reverberatory 10 chamber to be heated by the gases passing therethrough and a valve controlling the passage of fuel between the lower end of said tube and said coil.
3. A carbureter, comprising, in combination, inclosing walls forming inner reverberatory and outer gasifying chambers, said inner chamber being formed with an inlet and an outlet for the circulation of exhaust gases through said inner chamber and said 15 outer chamber having an inlet and an outlet for the admission of air and the egress of fuel mixture, said inner chamber having a fuel gasifying tube depending downwardly therein, the lower end of said tube being 20 adapted to be connected to a source of fuel supply and its upper end communicating with said outer chamber, a valve seated in said tube and adapted to control the opening and closing of said passage, a preheating 25 coil interposed between the lower and upper portions of said passage in said tube and removably connected by its ends to said tube, an electrical heater removably associated with said gasifying tube for heating 30 it and a bottom plate removably mounted upon the lower portion of the wall of said inner chamber whereby access can be gained to said inner chamber for the removal of said coil and heater.
4. A carbureter, comprising, in combination, inclosing walls forming inner reverberatory and outer gasifying chambers, said inner chamber being formed with an inlet and an outlet for the circulation of exhaust 35 gases through said inner chamber and said outer chamber having an inlet and an outlet for the admission of air and the egress of fuel mixture, said walls also forming a secondary chamber above said outer chamber; said inner chamber having a fuel gasifying tube depending downwardly therein and having its lower end adapted to be connected to a source of fuel supply and its upper end connected with said outer chamber, a gas 40 controlling valve seated between said outer and secondary chambers, a fuel supply valve seated in said tube and adapted to control the opening and closing of its passage and having a stem projecting upwardly and freely through said gas controlling valve, said stem being formed with a shoulder on its upper end and said gas controlling valve being provided with a push element extending 45 upwardly, whereby as said stem is raised said gas controlling valve is moved into open position, a lifting element movably mounted with an arm below said shoulder to raise said stem, said lifting element being provided with a cam surface against which the upper end of said push element is adapted to press to cause the moving of said stem through the raising movement of said gas controlling valve and means for regulating the movement of the upper end of said push element to vary the amount of opening of 50 said fuel supply valve.
5. A carbureter, comprising, in combination, inclosing walls forming inner reverberatory and outer gasifying chambers, said inner chamber being formed with an inlet and an outlet for the circulation of exhaust gases through said inner chamber and said outer chamber having an inlet and an outlet for the admission of air and the egress of fuel mixture, said walls also forming a secondary chamber above said outer chamber, said inner chamber having a fuel gasifying tube depending downwardly therein and having its lower end adapted to be connected to a source of fuel supply and its upper end connected with said outer chamber, a gas 55 controlling valve seated between said outer and secondary chambers, a fuel supply valve seated in said tube and adapted to control the opening and closing of its passage and having a stem projecting upwardly and freely through said gas controlling valve, said stem being formed with a shoulder on its upper end and said gas controlling valve being provided with a push element extending 60 upwardly, whereby as said stem is raised said gas controlling valve is moved into open position, a lifting element movably mounted with an arm below said shoulder to raise said stem, said lifting element being provided with a cam surface against which the upper end of said push element is adapted to press to cause the moving of said stem through the raising movement of said gas controlling valve, means for regulating the movement of the upper end of said push element to vary the amount of opening of said fuel supply valve, and means for adjusting said regulating means to cause the latter to vary the time of the opening of said fuel valve with relation to said gas controlling valve.
- In testimony whereof I have signed my name to this specification in the presence of two subscribing witnesses.
